(57) **CLAIM**

The ornamental design for a stainless steel container with lid, as shown and described.

DESCRIPTION

FIG. 1 is an exploded perspective view of a stainless steel container with lid;

FIG. 2 is a perspective view of a stainless steel container with lid;

FIG. 3 is exploded front view of a stainless steel container with lid;

FIG. 4 is a front view of a stainless steel container with lid;

FIG. 5 is an exploded rear view of a stainless steel container with lid;

FIG. 6 is a rear view of a stainless steel container with lid;

FIG. 7 is a top view of a stainless steel container with lid; and,

FIG. 8 is a bottom view of a stainless steel container with lid. The broken lines shown in the Figures depict environmental subject matter only and form no part of the claimed design.
